Attorney

UNITED STATES PATENT OFFICE.

LOUIS KOZELEK, OF SCHENECTADY, NEW YORK.

VIOLIN MUTE.

Application filed September 8, 1923. Serial No. 661,615.

To all whom it may concern:

Be it known that I, LOUIS KOZELEK, a citizen of the United States of America, residing at Schenectady, in the county of Schenectady and State of New York, have invented certain new and useful Improvements in Violin Mutes, of which the following is a specification.

This invention relates to improvements in violin mutes.

An important object of this invention is to provide a device of the above mentioned character which is adaptable to various positions to cause the production of various tones, such as a flute tone.

Another important object of this invention is to provide a mute which is simple in construction, durable, and one that could be placed upon the market at a reasonable cost.

Other objects and advantages of this invention will readily become apparent during the course of the following description, in which

25 Figure 1 is a top plan view of a violin with my device properly associated therewith,

Figure 2 is a plan view of the mute,

30 Figure 3 is a cross sectional view of the violin finger board and strings with the mute shown in operative position, and

Figure 4 is a transverse sectional view of the mute as it appears when placed between the violin finger board and the strings.

35 In the drawings, wherein for the purpose of illustration is shown a preferred embodiment of my invention, the numeral 5 indicates a violin having the usual tail piece 6 which is attached to the button 7. Attached to the tail piece 6 are the usual strings 8 which are stretched over the bridge 9 and along the finger board 10 to the keys or peg box 11 in which are carried the usual 40 keys or pegs 12 to which the violin strings 8 are connected.

Referring in particular to Fig. 2 in which is shown an enlarged view of my improved mute, the numeral 13 indicates the body portion, which may be formed by a plurality of woven strands of wool, cotton, silk or the like, which are cut into suitable lengths and the ends turned upon them-

selves as at 14 and secured by seizing the ends by a number of convolutions of strong 55 thread or the like as at 16.

In operation the mute is placed underneath the strings between the bridge 9 and the finger board 10, and by grasping the mute at the seized portion 16 it may be 60 forced between the strings 8 and finger board 10. It will be seen by referring to Fig. 3, that when in operative condition, the mute assumes a somewhat flat position. It is also to be understood, that the mute or 65 in other words all of the strands of twisted material need not be placed between the finger board 10 and strings 8 unless desired. The strands of the mute, may easily be separated and any number desired placed 70 between the finger board and the strings, while the remaining strands will pass along the underside of the finger board 10. Also, by placing the mute at a certain point spaced from the inner end of the finger 75 board 10 a sharp clear tone, such as produced by a flute, is obtained. Thus a two-tone instrument is produced and harsh, or over tones may be eliminated at will, by placing the mute in various positions, or 80 the clear sharp tone of a flute may be obtained. A person will, therefore, be able to obtain most any tone desired from a very loud tone to a very soft tone.

While I have shown and described the 85 preferred example of my invention, it is to be understood that various changes in the shape, size, and arrangement of parts may be resorted to without departing from the spirit of the invention or the scope of the 90 subjoined claims.

Having thus described my invention, I claim:—

1. In combination with a violin, of a mute 95 formed of soft pliable material to be adjustably positioned between the strings and finger board for causing variations in tone.

2. In combination with a violin, of a mute formed of twisted strands of material to be adjustably positioned between the 100 strings and finger board and held in such positions thereby for causing variations in tone.

In testimony whereof I affix my signature,

LOUIS KOZELEK.
